UNITED STATES PATENT OFFICE

**FREDERICK G. HAAGE, OF NEW YORK, N. Y., ASSIGNOR TO POWERS AND MAYER,
INCORPORATED, OF NEW YORK, N. Y.**

DESIGN FOR A WRIST-WATCH STRAP

Application filed May 2, 1929. Serial No. 31,077. Term of patent 3½ years.

To all whom it may concern:

Be it known that I, FREDERICK G. HAAGE, a citizen of the United States, residing at New York, in the county of New York and State of New York, have invented a new, original, and ornamental Design for Wrist-watch Straps, of which the following is a specification, reference being had to the accompanying drawing forming part thereof.

Figure 1 is a plan view of a wristwatch strap showing my new design.

Figure 2 is an edge elevation, and

Figure 3 is a plan view of the rear side of the wristwatch strap.

It is understood that the ornamental features shown in full lines are applied to the parts of the wrist watch strap shown in broken lines.

I claim:

The ornamental design for a wristwatch strap as shown and described.

FREDERICK G. HAAGE.
